UNITED STATES PATENT OFFICE.

EUGENE EDWARD FINNEGAN, OF CHICAGO, ILLINOIS, ASSIGNOR TO CONTINENTAL CAN COMPANY, INCORPORATED, OF SYRACUSE, NEW YORK, A CORPORATION OF NEW YORK.

COVER-OPENER FOR RECEPTACLES.

1,308,627.

Specification of Letters Patent.

Patented July 1, 1919.

Application filed February 2, 1916. Serial No. 75,689.

To all whom it may concern:

Be it known that I, EUGENE EDWARD FINNEGAN, a citizen of the United States, residing at Chicago, in the county of Cook, State 5 of Illinois, have invented certain new and useful Improvements in Cover-Openers for Receptacles, of which the following is a description, reference being had to the accompanying drawing and to the figures of reference marked thereon.

10 My invention relates to improvements in cover openers for receptacles, and consists in the matters hereinafter described and referred to in the appended claims.

15 The object of my invention is to provide a cover opener of this character in which the cover is readily opened and the opener is at all times carried by the cover and so arranged that it is supported by the cover, 20 wholly below the upper edge of the can.

Another object of my invention is to provide a simple, cheap and more effective 25 opener of this character having certain details of structure and combination of parts hereinafter more fully described.

In the accompanying drawings:—

Figure 1 is a top plan view of a can embodying my invention;

Fig. 2 is a vertical transverse sectional 30 view taken on the line 2—2 of Fig. 1;

Fig. 3 is a vertical transverse sectional view taken on the line 3—3 of Fig. 1; and

Fig. 4 is a perspective view of the cover removed, showing the means of supporting 35 the removing lever therein.

Referring now to the drawings, 1 represents a can which is of the usual type having a lateral flange 2, extending inwardly below the upper edge 3 thereof. This flange is of a 40 considerable width, as shown in Figs. 1 and 2 of the drawings, and is provided at its inner edge with an upwardly extending flange 4 forming a vertical wall for holding the cover.

45 The cover consists of a flat central portion 5 having at its outer periphery the upwardly extending flange 6 which engages the vertical flange 4 of the can and whereby the cover is frictionally held in the can. The 50 upper edge of the flange 6 is doubled into a horizontal flange 7 which limits the inward movement of the cover in the can and in the ordinary use serves as means for removing the cover.

55 The vertical flange 6 of the cover at the

point of junction with the flange 7 is provided with a horizontal slot 8 through which extends the removing lever 9. This is preferably made of a single piece of wire of sufficient strength to perform its function. The 60 piece of wire forming the lever is doubled in the center at 10 and having the two parallel portions 11 and 12 which are bent upwardly at 13. The ends of the parallel portions 11 and 12 are provided with laterally extending loops 15 and 16 extending in opposite directions in the same plane. These two loops form a broad surface to bear upon the flange 2 of the can and the parallel portions pass through the slot and rest upon the top of 70 the cover, and the doubled end 10 extends upwardly so as to form a finger hold so that the lever can be raised. The lever is fulcrumed in the slot and upon raising the doubled end 10 the outer end engages the 75 flange 2 of the can and the upper edge of the slot 8 and the cover is moved upwardly from within the friction flange of the can. When the cover is in position the lever is supported by the cover wholly below the upper edge of 80 the can. When the cover is removed the lever will hang in the slot, its shape preventing accidental displacement although, of course, if desired, the handle end may be withdrawn through the slot.

Having thus described the invention, what is claimed as new is:—

1. In combination with a can having a lateral flange extending inwardly below the upper edge of the can, the inner edge of 90 said flange being turned to form a friction wall, a cover having a vertical wall adapted to frictionally engage said wall on the flange, said wall on the cover having a slot there-through above the flange on the can, and a 95 lever disposed radially of the can and extending through said slot, said lever having lateral extensions at its outer end lying adjacent the flange and circumferentially of the can and extending beyond the ends of the 100 slot, the inner end of said lever being bent downwardly so as to lie adjacent the lever and prevent the outer end of the lever from passing over the edge of the can while said cover is in place, said lever bearing against 105 the flange on the can body as a fulcrum operating when raised to lift the cover from the can.

2. The combination with a can having a friction cover having an upstanding flange 110

provided with a horizontal slot adjacent its upper end, of a lever formed of a single piece of wire having a looped portion forming a broad can engaging end, and a handle portion curved downwardly therefrom and loosely passing through the slot and engaging the upper face of the cover and its end extending upwardly forming a finger hold

whereby the handle is raised and the cover removed from the can.

In testimony whereof, I affix my signature, in the presence of two witnesses.

EUGENE EDWARD FINNEGAN.

Witnesses:

GEORGE H. EDES,

GEORGE H. SPAULDING.
